Attorney.

Patented Feb. 15, 1927.

UNITED STATES PATENT OFFICE.

CORNELIUS EVAN JOHNSON, OF GRAND RAPIDS, MICHIGAN.

LOOSE-LEAF BINDER.

Application filed November 23, 1923. Serial No. 676,515.

The present invention relates to loose-leaf binders; and its object is to provide a device of that character improved in various respects hereinafter appearing; and more particularly, to provide such a device having improved means for locking the binding members thereof in contents-binding position but permitting their ready separation; and further, to provide such a device having improved features of construction.

These, and any other objects hereinafter appearing are attained by, and the invention finds preferable embodiment in, the structure hereinafter particularly described in the body of this specification and illustrated by the accompanying drawings, in which:—

Figure 1 is a longitudinal sectional view 20 of a portion of a loose-leaf binder, taken on a plane corresponding to line 1—1 of Figure 3;

Figure 2 is a like view of the same, but showing the covers open and certain parts 25 separated;

Figure 3 is a sectional view of a portion of the same taken on line 3—3 of Figure 1;

Figure 4 is a sectional view of certain parts taken on line 4—4 of Figure 3.

In the embodiment of the invention illustrated by the drawings, a loose-leaf binder is shown having covers 1, 2 connected by a flexible back 3. A pair of cooperating binding members 4, 5, bind or clamp the binder's contents—the leaves or sheets 6—between them, the lower binding member 5 engaging the under side of said contents and carrying posts 7 each of which is internally-screw-threaded as shown at 8. A hollow cylindrical element or sleeve 10 is adapted to receive the post which may be inserted longitudinally thereinto, said sleeve being insertable into openings 11 in the loose leaves 6. This sleeve has a lateral extension or radial flange 12 at its outer or upper end, of larger diameter than the leaves' openings 11 and therefore adapted to holdingly engage the opposite or upper side of the binder's contents, in the operative position of the parts seen in Figure 1. This sleeve may be withdrawn from the post with some of the loose leaves or sheets with it, other leaves or sheets remaining on the post, as seen in Figure 2, so that the leaves may 55 be separated at any point, each portion of the contents thus separated remaining in

connected relation either on the sleeve or on the post as seen in Figure 2. A screw 13 is threaded in the post and has a head 14 which may be freely received by, or passed 60 into and out of an opening 15 in the upper binding member 4. Means are provided for releasably holding the screw's head 14 when received into said opening 15; preferable means for so doing are particularly shown 65 in Figure 3, comprising a catch 17 carried by the upper binding member 4 slidably on rivets 18 extending through the catch's slots 19. This catch has an opening 20 with an enlarged portion 21 adapted to receive the head 14 of the screw and a contracted portion 22 adapted to hold this head 70 from releasing movement. In Figure 3 this catch is shown slid to the position in which the screws' heads are released and may be 75 withdrawn from the slots 20.

In the operative position of the device, shown in Figure 1, the screws are turned down in the posts to a position wherein they press the upper binding member 4 on the upper end of the sleeves or adjacent to their flanges or extensions 12, thus clamping the contents in the binder. When it is desired to open the binder to remove or insert leaves at any place, the catch 17 is moved to the position seen in Figure 3, whereupon the screws' heads may be withdrawn through the upper binding member's 80 openings 15 and through the sleeve; and when the desired removal or insertion of leaves has been made, the parts may be 85 returned to the operative position of the binder seen in Figure 1. In the drawings, a pair of posts, sleeves, etc. are shown, but it is manifest that any suitable number thereof 90 may be provided. In the illustrated construction, the binding members are flexibly connected at 25 and 26 respectively to the back 3.

The binding members 4 and 5 are desirably formed of a metallic strip 27 covered by a fabric sheath 28.

The invention being intended to be pointed out in the claims, is not to be limited to or by details of construction of the particular embodiment thereof illustrated by the drawings or hereinbefore shown or described.

I claim:

1. In a loose-leaf binder: a binding member engaging a side of the binder's contents and carrying an internally-screw-threaded

post; a sleeve adapted to receive the post and insertable into openings in said contents and having a lateral extension engaging the opposite side of said contents; a screw threaded in the post and having a head; a second binding member engaging the sleeve adjacent its extension and having an opening adapted to receive the screw's head; means for releasably holding the screw's head received in said second member's opening.

2. In a loose-leaf binder: a binding member engaging a side of the binder's contents and carrying an internally-screw-threaded post; a sleeve adapted to receive

the post and insertable into openings in said contents and having a lateral extension engaging the opposite side of said contents; a screw threaded in the post and having a head; a second binding member engaging the sleeve adjacent its extension and having an opening adapted to receive the screw's head; a catch carried by said second member slidably into and out of a position wherein it holdingly engages the screw's head. 25

In testimony whereof I have hereunto set my hand at Grand Rapids, Michigan, this 19th day of November, 1923.

CORNELIUS EVAN JOHNSON.
